MAGNETRON CASING

Percy L. Spencer, West Newton, Mass., assignor to
 Raytheon Manufacturing Company, Newton,
 Mass., a corporation of Delaware

Application December 17, 1941, Serial No. 423,307

3 Claims. (Cl. 250—27.5)

1

This invention relates to a magnetron casing, and more particularly to such a casing which is made of a metal, such as copper, and is provided with a special end construction to increase the effective magnetic field within the magnetron.

In magnetron tubes of the conductive envelope type, the magnetic field is impressed on the tubes by magnetic poles placed adjacent the opposite ends of the tube. Thus there is an effective air gap between the poles extending the entire length of the magnetron. The metallic walls of the envelope must necessarily be of a certain thickness in order to possess the requisite rigidity to withstand the differential atmospheric pressure inside and outside of the tube. This length of air gap makes it difficult to produce magnetic fields of the desired high intensity in the discharge space within the magnetron.

An object of this invention is to devise a magnetron casing in which the effective air gap length between the magnetic poles is substantially decreased.

Another object is to produce such a structure in which the reduction in air gap is accomplished by the use of highly magnetic end caps provided with means whereby these caps may be readily secured in place as by soldering.

The foregoing and other objects of this invention will be best understood from the following description of an exemplification thereof, reference being had to the accompanying drawing, wherein:

Fig. 1 is a vertical cross-section through a magnetron incorporating my invention, taken along line 1—1 of Fig. 2; and

Fig. 2 is a top view of the magnetron as illustrated in Fig. 1.

The magnetron illustrated comprises an envelope 1 which is preferably made of a block of non-magnetic conductive material, such as copper. This block forms the anode of the magnetron, and is provided with hollow end sections which are covered by end caps 2 and 3, likewise of conductive material. Between the hollow end sections of the envelope 1 is the central bridging portion 4. The portion 4 is provided with a central bore 5 within which is supported substantially at the center thereof a cathode 6, preferably of the indirectly-heated oxide-coated thermionic type. The cathode 6 is supported by a pair of cathode lead-in conductors 7 and 8 sealed through the ends of glass chambers 9 and 10 on the outer ends of pipes 11 and 12 hermetically fastened within the walls of the envelope 1 adjacent the upper and lower hollow end sections.

2

An additional lead 13 may be provided to extend from a suitable coupling means within the envelope 1, whereby high frequency oscillation generated within the device may be conducted to a suitable utilization device. The lead 13 may likewise be sealed through the outer end of a glass chamber 14 mounted at the outer end of the pipe 15 likewise hermetically sealed within the walls of the envelope 1. The magnetron is designed and intended to be placed between suitable magnetic poles 16 and 17 to create a longitudinal magnetic field passing through the space between the cathode 6 and the surrounding walls of the bore 5, constituting the anode structure for said cathode.

If the end caps 2 and 3 were made entirely of copper, it will be seen that the air gap between the poles 16 and 17 would extend the entire length of the envelope 1. Since it is desired to create high intensities of magnetic fields within the discharge space around the cathode 6, the presence of a relatively long air gap makes it difficult to set up fields of the desired intensity. Thus any way in which the length of this air gap can be decreased will greatly increase the effectiveness of the magnetron device. However, as already indicated, it is necessary that the wall thickness of the end caps 2 and 3 be a substantial value in order to withstand the atmospheric pressure exerted upon them. One way in which the air gap might be decreased would be to make the end caps entirely of a magnetic material, such as iron. However, if the end caps were made entirely of iron, serious difficulties would arise in attempting to hermetically seal the iron end caps to the copper walls of the envelope 1. In accordance with my invention, the end caps, for example the upper cap 2, is made of a thin copper sheet 18 formed into a cup shape fitting relatively snugly within the open upper end of the envelope 1. A plate 20 of a magnetic material, such as iron, is fitted into the upper open end of the cup thus formed. The plate 20 may be fastened within the cup in any suitable way, as by soldering, so as to form a composite wall of the requisite physical strength. However, it is not necessary to have the connection between the iron plate 20 and the copper sheet 18 in any way hermetic inasmuch as the copper plate 18 in itself forms an imperforate and impermeable wall against the passage of atmospheric gases into the device. The plate 18 may be sealed to the wall of the envelope 1 along the joint 22 in some suitable way, as by silver solder. This method of sealing two copper members together so as to

form a hermetic seal has been very satisfactory and effective. In a particular embodiment I have made the sheet 18 of a copper sheet .015 of an inch thick, while the plate 20 could be of a substantially greater thickness, for example one-eighth of an inch. The end cap 3 is made identical with that of the end cap 2, and comprises a copper sheet 19 with a magnetic insert 21.

Of course it is to be understood that this invention is not limited to the particular details of construction as described above as many equivalents will suggest themselves to those skilled in the art. For example, instead of having the magnetic plates extend across substantially the entire end of the magnetron, they could be of a more limited extent so as to concentrate the magnetic field in the device more nearly along the central bore 5, where the greatest concentration of the field is desired. Also the principles of this invention might be applied to various other types of devices utilizing the magnetic field in which the size of the envelope plays a substantial part in limiting the magnetic field by introducing a substantial air gap.

What is claimed is:

1. A magnetron comprising a hollow envelope of a substantially non-magnetic metal containing cooperating electrode elements, said magnetron being designed and adapted to have a magnetic field set up in the space between said electrode elements, said envelope having an end cap

sealed to and closing one end of said hollow envelope, said end cap comprising a sheet of a substantially non-magnetic metal and an insert of magnetic material set into said sheet to decrease the gap space through which said magnetic field must pass.

2. A magnetron comprising a hollow envelope composed substantially of copper and containing cooperating electrode elements, said magnetron being designed and adapted to have a magnetic field set up in the space between said electrode elements, said envelope having an end cap sealed to and closing one end of said hollow envelope, said end cap comprising a sheet of copper and an insert of magnetic material set into said sheet to decrease the gap space through which said magnetic field must pass.

3. A magnetron comprising a hollow envelope composed substantially of copper and containing cooperating electrode elements, said magnetron being designed and adapted to have a magnetic field set up in the space between said electrode elements, said envelope having an end cap sealed to and closing one end of said hollow envelope, said end cap comprising a sheet of copper and an insert of magnetic material set into said sheet to decrease the gap space through which said magnetic field must pass, said sealing being made between the copper part of said end cap and the copper of said envelope.

PERCY L. SPENCER.
